UNITED STATES PATENT OFFICE.

PETER G. MACGREGOR, OF NEW YORK, N. Y.

DESIGN FOR A BRACKET FOR HOLDING FIRE-EXTINGUISHERS OR SIMILAR ARTICLES.

44,015.

Specification for Design.

Patented May 13, 1913.

Application filed February 13, 1913. Serial No. 748,249. Term of patent 7 years.

To all whom it may concern:

Be it known that I, PETER G. MACGREGOR, a citizen of the United States, and resident of the city, county, and State of New York, have invented a new and original ornamental Design for a Bracket for Holding Fire-Extinguishers or Similar Articles, of which the following is a specification, reference being had to the accompanying drawings, forming part thereof.

The Figures 1 and 2 of the drawing are front and side elevations, respectively, of a bracket, showing my new design therefor.

The design comprises a rectangular base

having a web centrally located and extending at right angles therefrom. A cup-shaped support is attached to the lower portion of this web and curved arms extend from the upper portion thereof, as substantially shown in the drawings.

I claim:

The ornamental design for a bracket for holding fire extinguishers, or similar article, as shown and described.

PETER G. MACGREGOR.
